UNITED STATES PATENT OFFICE.

STRICKLAND L. KNEASS, OF PHILADELPHIA, PENNSYLVANIA, ASSIGNOR TO WILLIAM SELLERS & COMPANY, INCORPORATED, OF PHILADELPHIA, PENNSYLVANIA, A CORPORATION OF PENNSYLVANIA.

INJECTOR.

Application filed June 30, 1923. Serial No. 648,651.

To all whom it may concern:

Be it known that I, STRICKLAND L KNEASS, a citizen of the United States, residing at Philadelphia, county of Philadelphia, and State of Pennsylvania, have invented a new and useful Improvement in Injectors, of which the following is a full, clear, and exact description, reference being had to the accompanying drawings, which form a part of this specification.

My invention relates to injectors, such, for example, as are used for supplying feed water to steam boilers.

The object of my invention is to provide an improved injector whereby the latent heat in exhaust steam will be utilized as a motive agent to assist in feeding a steam boiler, as, for example, a locomotive boiler, and at the same time whereby the heat units in such exhaust steam will be returned to the boiler.

I accomplish the objects of my invention by means of certain relatively proportioned receiving and discharging nozzles, inlet areas for water and openings for discharge, so as to obtain from the waste heat of exhaust steam sufficient energy to establish a continuous jet of water and condensed steam passing through the nozzles, resulting in a terminal pressure much above that of the initial pressure of the exhaust steam. The jet is discharged into the receiving chamber of a live steam injector under such pressure as to enable it to receive and force water, at a higher temperature than heretofore, against initial boiler pressure.

More particularly, the object of my invention is accomplished by means of a novel and simple combination of tubes and nozzles so proportioned and pierced by narrow lateral openings protected from external pressure and separated by self-closing valves, so that the jet within the heater nozzles is capable of rejoining and automatically re-establishing the jet in case of excess counter pressure produced by the live steam injector. At the same time, the up-

ward flow of the supply water through the exhaust steam nozzle into the exhaust pipe or cylinders is prevented by the special location of the lateral openings.

By virtue of my invention, it will be noted a large percentage of heat from a waste product is obtained and there is established a continuous injection of feed water into the boiler at such a high temperature that the efficiency of the steam producing plant is increased, while at the same time internal strains are so reduced as to materially lessen the cost of maintenance.

It will also be noted that the results obtained by my invention are obtained with simplicity of construction and manipulation and a reduction in attention necessary on the part of the operator.

Having now indicated, in a general way, the nature, purpose and advantages of my invention, I will proceed to a more detailed description of a preferred embodiment thereof, with reference to the accompanying drawings, in which—

Fig. 1 is a vertical sectional view of a device embodying my invention.

Fig. 2 is a sectional view on line 2—2 Figure 1.

Fig. 3 is a sectional view on line 3—3 Figure 1.

a represents a casing provided with an inlet *b* for the admission of exhaust steam to a steam nozzle *b'* which discharges into a combining tube *c*, having the form of a Venturi tube. The combining tube is provided in its upper portion with a narrow lateral opening *d* affording communication with an overflow chamber *e*, and in its middle and lower portions with narrow lateral openings *f* and *f'* affording communication with an overflow chamber *g*. Outlet from the chamber *e* into the chamber *g* is through a check valve *h* and final outlet from chamber *g* to the air is through a check valve *i*. The combining tube forms at its lower end a delivery nozzle *c'* Ad- jacent the upper end of the combining tube

c is a water chamber *j* provided with a water inlet *k* controlled by a valve *l*. A narrow annular opening *m* is provided for the passage of water from the water chamber into the combining tube.

The construction of the overflow chambers *c* and *g* and their special use with the protecting check valve *h* is novel in any jet apparatus in the form of a Venturi tube operated by exhaust steam where the proportional area of the steam admission nozzle is ten or more times than that of the delivery tube, and larger than that of the venturi at the upper lateral aperture. It prevents any injurious influence from the discharge from the lower lateral apertures of the combining tube, permits a wider range of proportions between the water and steam supplies, and renders the operation more positive. Further, the upper lateral aperture *d* may be placed nearer the end of the steam nozzle, rendering the apparatus more easy to start under all conditions, especially when the pressure of the steam exceeds that of the head of the water supply. In cases of similar separation in high pressure injectors, such as the use of a special valve protecting the space between the lower end of its draft and the upper end of its combining tube, the location of this space or opening is at a cross-sectional part of the tubes considerably larger than the limiting area of the steam nozzle, essential for the purpose of producing a partial vacuum in the water supply chamber during steam discharge.

Further, the construction includes the discharge of fluid from the upper lateral aperture *d* of the low pressure venturi into the lower chamber *g* so that in case there be a lower absolute pressure within this chamber, the upper check *h* will open and any waste will be entrained by the moving jet through the lower apertures *f* and *f'* of the venturi. The construction also gives the advantage of double protection against influx of air to the upper lateral aperture as any leakage must pass under the two check valves *h* and *i*.

Adjacent the lower end of the delivery tubes *c'* is a live steam chamber *n*, provided with a live steam inlet *o* and a steam nozzle *p* in communication with a series of forcing tubes *q* forming a Venturi passage.

A chamber *r* adapted to receive water from the delivery tubes *c'* of the heater nozzles is in communication with the forcing tubes *q*, the flow of water being controlled by a check valve *s*.

The forcing tubes *q* are provided with several narrow lateral openings *t* which afford an outlet for overflow into a chamber *u* and finally to the air through check valve *v*.

The forcing tubes are provided at the upper end with a terminal check valve *w*, which

controls the discharge into a final delivering chamber *x*, from whence the water passes to feed a boiler through feed pipe *y*.

The operation of the device will be understood from the following:

Exhaust or low pressure live steam from an engine cylinder is admitted through the inlet *b* in the body or casing *a*, flows through the steam nozzle *b'* and the upper narrow lateral opening *d* of the combining tube to the upper overflow chamber *e*, and discharges in part under the upper overflow check valve *h*; another portion of the steam flows through the middle and lower narrow lateral openings of the combining tube into the lower overflow chamber *g*, both portions finding outlet to the air by lifting and discharging from under the final overflow check valve *z*. This flow from the engine cylinder may be allowed to occur during the time that the engine is in operation, as the device may be used with or without an intercepting valve between the exhaust supply and the body or casing, since the waste pipe may be connected in such manner as to not cause inconvenience to the operator by the outflow of steam.

Water supply is admitted by opening the valve *l*, entering the water chamber *j* of the injector body under a head or pressure; it passes in a thin sheet through the narrow annular space *m*, between the outer walls of the exhaust steam nozzle *b'* and the inner wall of the upper part of the combining tube *c*; contact with the inflowing steam immediately causes condensation, producing a high vacuum, which increases the inflow of both the steam and of the water. The resultant jet discharges with rapid acceleration, due to the continued impulsive action of the steam, past the upper narrow lateral aperture *d* and through the convergent parts of the combining tube, through the narrow throat of its delivery nozzle *c'*, producing a head in the chamber *r* of many times that of the initial pressure within the exhaust steam supply pipe.

In case of surplusage of water, due to the position of the water supply valve *l*, or incorrect location of the exhaust steam nozzle relative to the cross section of its combining tube or insufficient steam pressure, waste will occur through a narrow lower lateral opening *f* into the overflow chamber *g*, pass under the lower overflow check *i* to the air; as will occur in case of operation against excessive counter pressure, without destroying the continuous action of the jet within the upper parts of the combining tube.

During this continuity of the jet, a partial vacuum within the combined upper part of the combining jet caused by condensation of the inflowing steam is communicated to the upper overflow chamber *e*,

which is sealed against air entering by the tight closure of the upper overflow valve *h*.

The water forced by the exhaust steam heater into its delivery chamber *r*, is raised 5 to a high temperature, lifts the check valve *s*, and enters the receiving chamber *n* of the live steam forcing set of tubes and nozzles from which outflow may be obtained through the several narrow lateral openings 10 *t* in the tubes to their overflow chamber *u*, finding outlet to the air by passing under the final overflow valve *v*.

To complete the required series of operations, live steam from the boiler is admitted 15 to the chamber *n* through the opening *o*, discharges through a small guiding nozzle *p*, which forces the entering water from the exhaust steam heater through a series of convergent and divergent tubes *q*, and lifts 20 the terminal check valve *w*, discharging through the final delivery chamber *x* into the boiler feed pipe *y*. The narrow lateral apertures *t* within and at the end of the forcing tubes *q* are proportioned so as to give 25 free relief to the live steam discharging from the nozzle *p* in case of temporary interruption of the water or steam supply. Under certain conditions when the terminal overflow check valve of the live steam set 30 of tubes is free to open, the combined heater and injector is able to restart automatically without the attention of the operator.

In a case where the terminal overflow check valve *w* is held tightly to its seat by 35 means of the screw stem, free outlet to the atmosphere from the overflow of the live steam tubes is closed and might produce an excessive counter pressure against the action of the jet of the exhaust steam heater; but 40 the consequent return or back flow of steam or water from the live steam tubes is prevented by the automatic closure of the check valve *s*; this closure of the delivery check of the exhaust steam heater prevents back 45 flow from the live steam set through the delivery tube of the exhaust steam heater and only produces a counter pressure against which the heater cannot operate; this results in waste of water and condensed steam 50 from the lower overflow of the exhaust heater which finds outlet under the check valve *z* of the lower overflow chamber without interfering with the continuity of the jet of the exhaust steam heater within the upper 55 parts of the combining tubes so that by releasing the overflow check valve of the live steam set so as to permit relief of pressure within its overflow chamber, the combined device will restart automatically.

60 It is well known that the use of a waste product is of economical advantage and by applying exhaust steam as a motive power, a percentage of the heat wasted in a steam engine or locomotive can be retrieved, and 65 this amount or percentage depends upon the

relative proportions of entering steam and water supply. It is also known that the ability of a live steam injector to receive and deliver warm water against initial pressure depends upon the velocity and the thickness of the annular sheet of water at the limiting area of the receiving end of the live steam combining tube. To obtain this end, the pressure produced by the exhaust steam heater nozzles is made as high as 70 practicable and the constricted area between the discharging end of the live steam nozzle and its combining tube is made very narrow so as to produce a thin annular cone of water entering the live steam combining tube, 75 which results in a large condensing surface for the live steam jet. By means of the proportions of nozzles and tubes, I have obtained a high temperature of delivered water 80 from the exhaust steam heater, which enters the live steam combining tube with great velocity, and is discharged into the boiler at a temperature not far below the temperature of that of the initial live steam. Under such conditions, there will be pressure above the 85 atmosphere in the overflow chamber surrounding the combining tube of the live steam set of tubes which would cause an outflow of hot water and steam from the terminal waste pipe, but this I prevent by closure of the final overflow which may be by hand or by suitable device.

Having now fully described my invention, what I claim and desire to protect by Letters Patent is:

1. A steam boiler feeder comprising, in combination, an injector comprising a steam nozzle, a combining tube provided with a lateral overflow opening positioned at a point where the cross sectional area of the tube is substantially smaller than the minimum diameter of the steam nozzle and greater than the area of the water entrance, means to prevent influx through said opening, and a delivery tube operated by low pressure steam, a second injector comprising a steam nozzle, a combining tube and a delivery tube operated by high pressure steam, a passage affording communication from said first mentioned injector to said second injector and a check valve in said passage adapted to prevent reflux.

2. A steam boiler feeder comprising, in combination, an injector, comprising a steam nozzle, a combining tube and a delivery tube operated by low pressure steam, delivering to a second injector operated by high pressure steam and comprising a steam nozzle, a combining tube and a delivery tube, a check valve adapted to prevent reflux from the latter injector, a lateral opening in the combining tube of the low pressure injector positioned at a point where its cross sectional area is smaller than that of the steam nozzle and greater than the area 130

of the water entrance to the combining tube, a chamber enclosing said opening, a second chamber in communication with the said first chamber, a second opening in said combining tube positioned between said first mentioned opening and the point of minimum diameter of the low pressure delivery tube, said chamber being provided with a port to the air, and outwardly opening check

valve controlling said port, a lateral opening in the high pressure combining tube, a chamber surrounding said opening having an outlet port to the air, and a check valve to prevent influx through said port. 10

In testimony of which invention, I have 15 hereunto set my hand, at Philadelphia, Pa., on this 27th day of June, 1923.

STRICKLAND L. KNEASS.
